UNITED STATES PATENT OFFICE.

ARTHUR W. SMITH, OF NEW YORK, N. Y., ASSIGNOR, BY MESNE ASSIGNMENTS, TO REMINGTON TYPEWRITER COMPANY, OF ILION, NEW YORK, A CORPORATION OF NEW YORK.

TYPE-WRITING MACHINE.

1,147,821.

Specification of Letters Patent. Patented July 27, 1915.

Application filed November 9, 1912, Serial No. 730,350. Renewed January 28, 1915. Serial No. 4,964.

To all whom it may concern:

Be it known that I, ARTHUR W. SMITH, citizen of the United States, and resident of the borough of Manhattan, city of New York, in the county of New York and State of New York, have invented certain new and useful Improvements in Type-Writing Machines, of which the following is a specification.

10 My invention relates to typewriting machines and more particularly to tabulating mechanism.

One of the main objects of the invention is to provide denominational tabulating mechanism operative or effective during a portion only of the travel of the carriage and column selecting mechanism operative or effective only at another portion of the travel of the carriage.

20 A further object of the invention is to provide key controlled tabulating mechanism including means operating automatically to enable the key or keys for such mechanism to operate in one instance for denominational selection and in another instance for column selection.

A still further object of my invention is to provide tabulator indicating means which are automatically shifted to bring different 30 indices into use.

Another object of the invention is to provide tabulator mechanism which is operative at one time as a denominational selector and at another time as a column selector and 35 to combine therewith tabulator indicating means which are automatically shifted as the tabulating mechanism is rendered effective for one of said purposes instead of the other.

40 Another object of my invention is to provide a traveling tabulator stop which moves at a different rate of speed from the carriage.

Still another object of my invention is to 45 provide a traveling tabulator stop and means by which the speed of said stop may be varied relatively to that of the carriage.

A further object of my invention is to 50 provide features of construction of the character specified which are applicable to existing forms of typewriting machines and to the tabulating mechanism embodied in such machines without modifying, or materially

modifying, the machines and the tabulating mechanism of such machines as they now 55 exist.

To the above and other ends which will hereinafter appear, my invention consists in the features of construction, arrangements 60 of parts and combinations of devices set forth in the following description and particularly pointed out in the appended claims.

In the accompanying drawings wherein like reference characters indicate corresponding parts in the various views, Figure 65 1 is a fragmentary side elevation with parts in section of one form of typewriting machine embodying my invention. Fig. 2 is a detail bottom plan view with parts in section, the view showing a part of the tabulator mechanism and the automatically actuated means for shifting the indicator. Fig. 3 is a fragmentary plan view of the machine with parts omitted and parts broken away. Fig. 4 is a horizontal sectional view of the 70 machine with parts omitted, the section being taken on the line $x-x$ of Fig. 1 and looking in the direction of the arrows at said line. Fig. 5 is a detail fragmentary central transverse sectional view of one of the 75 sprocket wheels and the adjustable means on which the wheel is mounted and by which it may receive a bodily adjustment. Fig. 6 is a fragmentary detail front view with parts in section of the tabulator indicator 80 and the means by which it is shifted. Figs. 7, 8 and 9 are detail top plan views of three different sizes of driving sprocket wheels for the sprocket chain, which wheels are interchangeable on the driving shaft. Fig. 10 85 is a detail central sectional view of the sprocket wheel shown in Fig. 8 and the means by which it is detachably fixed to the driving shaft. Fig. 11 is a detail diagrammatic view showing the indicator and a 90 modified arrangement of the shifting means therefor. Fig. 12 is a face view of the indicator plate shown removed from its carrier. Fig. 13 is an enlarged detail fragmentary top plan view of the sprocket chain 100 at the point of connection therewith of the traveling stop and showing a portion of the guide for the chain.

I have shown my invention in the present instance in a No. 11 Remington machine in 105 which the invention may be readily em-

bodied without modifying, or materially modifying the structural features of that machine as they now exist. It should be understood, however, that the invention may be embodied in various forms of typewriting machines and that certain features may be employed without others.

The frame of the machine comprises a base 1, corner posts 2 and a top plate 3. A carriage 4 (conventionally represented) is mounted on anti-friction balls or rollers 5 to travel from side to side of the machine over said top plate. The carriage carries a cylindrical platen 6 and upwardly and rearwardly striking type bars 7 are adapted to strike against the front face of the platen.

Rearwardly extending bracket arms 8 are secured by screws 9 to the carriage and are connected at their rear ends to a column stop bar 10 provided with teeth 11 on the upper and lower sides thereof for the reception of column stops 12 in the interdental spaces between said teeth. Arms 13 are pivoted at 14 to the carriage and are connected at their rear ends to a feed rack 15 which meshes with a feed pinion 16. This pinion is mounted on the forward end of an escapement wheel shaft 17 mounted to turn in a bearing 18 secured to the top plate of the machine. The rear end of the escapement wheel shaft carries an escapement wheel (not shown) with which the usual feed dog coöperates.

A series of tabulator keys 19 are provided with key stems 20 which are guided in upper and lower guide plates 21 and 22 respectively. Each key stem is operatively connected with an angular lever 23, the depending arm 24 of which is connected to one end of a contractile spring 25 which has its opposite end connected to the guide plate 22. Each depending arm 24 is also connected to a rearwardly extending link 26 which is connected at its rear end to a tabulating stop device or member designated as a whole by the reference numeral 27. Each of these tabulating devices 27 is in the nature of a lever pivoted at 28 intermediate the ends thereof in a tabulator frame 29 fixed to the frame of the machine. The upper end of each lever extends toward the front of the machine, as at 30, to form a denominational stop which, when projected forwardly, is adapted to coöperate with one of the column stops 12. The denominational stops are projected through a guide comb 31 which is secured to the tabulator frame 29. A universal release bar 32 is connected at its ends to arms 33 which are pivoted at 34 on a pivot rod which also constitutes the pivot for the angular levers 23. A rearwardly extending link 35 is connected to each of the depending arms 33 and extends rearwardly to a crank arm 36 to which it is pivoted. The crank arms 36 are fixed to and extend downwardly from a rock shaft 37 mounted for

pivotal movement in the base of the machine. A crank arm 38 is also fixed to the rock shaft 37 and extends downwardly and then forwardly and upwardly, as shown in Fig. 1, where it is pivotally connected as at 39 with a link 40. The upper end of this link is pivotally connected to an arm 41 which constitutes a part of the frame 42 pivoted at 43 in the arms of a bracket 44, which latter is secured by a screw 45 to the top plate of the machine. This frame 42 has formed as a part thereof a bearing 46 for a shaft 47. This shaft is provided at its forward end with a pinion 48 and the rear end of this shaft has a bevel pinion 49 fixed thereto. In the normal positions of the parts the pinion 48 is arranged beneath the feed rack 15 of the machine and out of mesh therewith. When, however, the frame 42 is rocked on its pivots the pinion 48 is thrown into mesh with the feed rack and the upward pressure on the feed rack is effective to disengage it from the feed pinion 16 to release the carriage from control of the escapement mechanism. At the same time the bevel pinion 49 is thrown into mesh with a coöoperative bevel pinion 50. The pinion 50 is secured to the upper end of a shaft which turns the casing 51 and which is provided at its lower end with arms or blades which rotate within a fixed casing 52 secured to the top plate of the machine. Suitable material such as shot, for example, may be contained within the casing 52 so that the parts constitute a retarding device which is thrown into operation when the carriage is released from its escapement mechanism and is moved from right to left under the power applied thereto by the usual spring drum 53. This drum is connected to the carriage by means of a band 54 connected at one end to the drum and at its opposite end to an arm 55 fixed to the carriage.

It will be understood from the foregoing description that an actuation of the tabulator key 19 is effective to actuate the corresponding angular lever 23 to transmit movement to the stop lever 27 which is connected therewith, thus moving the corresponding denominational stop 30 into the path of the column stops on the carriage. At the same time the universal release bar 32 is moved rearwardly, thereby rocking the shaft 37 and transmitting a forward rocking movement to the arm 38, which movement is effective to rock the frame 42, thus releasing the carriage and throwing the carriage retarder into operation.

The parts thus far described are the same as those embodied in the No. 11 Remington machine except that in some instances the parts of the carriage construction have been conventionally represented. Moreover, the shape of the arm 38 has been slightly changed in order to accommodate itself to other parts

which have been introduced into the machine, as will be hereinafter more fully explained.

A supporting plate 56 is fixed to the frame 5 of the machine by supporting screws 57. These supporting screws are those usually employed in the machine for holding the key lever returning springs in place except that they are slightly modified to act as 10 fastening devices for the supporting plate 56. Each of the supporting screws 57 is threaded at its upper end where it is received in a tapped opening in a cross bar 58 which forms part of the base of the machine. Each screw is formed with a hexagonal or octagonal portion 59 by which the screw may be threaded into the tapped opening in the cross bar. A spacing sleeve 60 surrounds the screw below the part 59 and 15 against which the sleeve bears. The plate 56 has an opening through which the reduced threaded end 61 of the screw 57 extends, a nut 62 co-operating with the threaded end 61 to secure the plate 56 in place. 20 There are two of these screws 57, one at each side of the machine, and in addition to the usual functions performed thereby they constitute means by which the supporting plate 56 is fixedly held in place. This supporting plate 56 constitutes a bearing or 25 supporting member on which various parts of what may be termed the auxiliary tabulating mechanism and the automatically actuated means for controlling the tabulator indicator are mounted. Thus, for example, the plate is tapped to receive a shouldered pivot screw 63 (Fig. 4) which constitutes a pivot for a band or sprocket wheel 64. This wheel has a hub 64^a which 30 bears against the plate 56 and maintains the body portion of the wheel preferably spaced away from the plate. An endless band, which in the present instance is in the nature of a sprocket chain 65, surrounds this 35 sprocket wheel and also surrounds a second band or sprocket wheel 66. The wheel 66 is mounted to turn on a pivot bearing 67 which is in the nature of an eccentric provided with a flange 68 (see Fig. 5) which 40 overlaps the wheel 66 at the lower side thereof to hold the wheel 66 in place with the hub 69 thereof bearing against the supporting plate 56. A screw 70 extends through an eccentrically arranged opening 45 in the bearing member or eccentric 67 and is received in a tapped opening in the supporting plate 56. The head 71 of the screw is provided with a crank arm or finger piece 72 by which the screw may be turned to 50 secure the eccentric in the rotative position to which it may be adjusted. It should be understood that the thickness of the eccentric 67 is such that when the head 71 is screwed up tight against it the screw will 55 secure the eccentric against rotative move-

ment but that the wheel 66 will be adapted to rotate freely on the eccentric. By this construction the eccentric 67 may be rotatively adjusted to any desired position on the screw 70 and secured by the screw in the 70 rotative position to which it has been adjusted. Means are thus provided by which the wheel 66 may be shifted bodily toward and away from the wheel 64 in order to provide more or less slack in the sprocket chain 75 65, as will hereinafter more clearly appear. The endless flexible band or sprocket chain 65 also meshes with a driving sprocket wheel 73 which is detachably fixed to a driving shaft 74 by means which are clearly 80 shown in Figs. 8 and 10. From these figures it will be observed that the upper face of the sprocket wheel 73 is provided with a circularly arranged series of radiating depressions 75, this portion of the wheel constituting in effect one section of a two-part clutch member. The other section of this clutch comprises a disk 76, the lower face of which is provided with circularly arranged radiating teeth 77 which are adapted to be 85 received in the depressions 75 to effect an interlocking connection between the sprocket wheel 73 and the disk 76. This disk has a hub 78 fixedly connected to the driving shaft by means of a pin 79. The hub 78 is received in a bearing opening 80 in the supporting plate 56, whereas the upper face of the disk 76 is adapted to bear against the lower face of the supporting plate to prevent an upward displacement of the driving 100 shaft 74 and the parts carried thereby. The lower face of the driving wheel 73 is provided with a hub 81 against which a nut 82 is adapted to bear to maintain the wheel 73 in such position that the teeth 77 will remain 105 seated in the depressions 75, so that the driving shaft and wheel 73 are fixed to turn together. The nut 82 is received on the lower threaded end of the driving shaft and is provided with laterally projecting pins 83 110 which constitute a finger piece by which the nut may be turned to release the clutch, and by which the nut when desired may be removed from the driving shaft to enable either of the wheels 73^a or 73^b shown in Figs. 115 7 and 9, respectively, to be substituted for the wheel 73. The purpose of substituting one of these wheels for another will hereinafter more clearly appear.

The upper end of the driving shaft 74 extends through a bearing opening in the top plate of the machine and has a gear wheel 84 secured thereto. This gear has a long hub 84^a tapped to receive set screws 85 which bear at their inner ends against the driving 120 shaft 74 to fixedly connect the gear to the shaft. The lower end of this hub bears against the top plate to support the driving shaft and the parts carried thereby in place. The gear 84 meshes with a rack 86 which 130

extends longitudinally of the carriage throughout the length thereof and is fixed by screws (Fig. 3) to the bracket arms 8 which support the column stop bar on the carriage. From an inspection of Fig. 3 it will be observed that the driving gear 84 and the driving sprocket 73 are of the same, or substantially the same, pitch so that with the employment of the sprocket wheel 73 a linear movement of the chain 65, corresponding to the travel of the carriage, is effected by the movement of the carriage.

A guide plate, designated as a whole by the reference numeral 87, is pivoted at 88 to the supporting plate 56 and extends at an inclination from its pivot to the driving sprocket, as shown in Fig. 4, the guiding surface 89 extending in the general direction of the chain in its movement from one sprocket wheel 64 to the other sprocket wheel 66 but at a slight inclination to the chain. This guide member is preferably made of sheet metal and is formed with a guiding surface 89 which extends at right angles from the body portion 90 of the guide. The body portion of the guide is bifurcated or slotted at 91 where it receives a shouldered thumb screw 92 which is threaded into a tapped opening in the plate 56. The shoulder 93 on the screw is adapted to bear against the body portion 90 of the guide and bind it against the supporting plate 56 in order to secure the guide in any one of several positions to which it may be adjusted toward and from the axis of the rock shaft 74, such adjustment of the guide being effected around its pivot 88. From an inspection of Fig. 4 it will be understood that when the guide 87 is maintained in place, the sprocket chain will be guided by the surface or flange 89 and maintained against movement away from or out of mesh with the driving sprocket 73. When, however, the thumb screw 92 is released the guide may be moved away from the sprocket wheel, thereby enabling the sprocket chain to be deflected laterally away from the driving sprocket 73 and out of mesh therewith. If necessary the eccentric 67 may be turned to afford sufficient slack in the chain to enable this deflection of the chain out of mesh with the driving sprocket to be effected. It will be understood that when the chain is out of mesh with the driving sprocket the chain may be moved longitudinally in order to effect an adjustment of a traveling tabulator stop or contact device 94 which is carried by the sprocket chain. The chain being disconnected from the driving sprocket in the manner described and a longitudinal movement of the chain being effected, it will be understood that any suitable adjustment of the stop 94 relatively to the carriage may be effected. From an inspection of Fig. 13 it will be understood that the tabulator stop

94 is in the nature of a sheet metal plate which constitutes a part of one of the links of the endless chain and has an engaging or stop portion 95 and a projection 96 which overlaps a member 97 of an adjacent link. When the parts are in the position shown in Fig. 13 the projection 96 will tend to resist a turning action of the stop 94 or a flexing of the chain at this point, as will hereinafter more clearly appear. This stop 94 is adapted to travel through a slot 98 which extends longitudinally throughout the length of a fixed guide 99 which surrounds the chain on three sides and is secured in place on the supporting plate 56 by screws 100. It will be understood that the surrounding walls of this guide prevent the chain from being flexed within the guide and constitute means which resist a turning movement of the stop 94 when the latter is brought into coöperation with the stop members with which it co-acts. From an inspection of Fig. 13 it will be understood that the construction of the stop 94 is such that the projection 96 on the stop 94 coöperates with the member 97 of the adjacent link of the chain to resist a turning movement of the stop when the latter is brought into co-operation with the arresting means which coöperates therewith. The turning movement or flexion of the adjacent link is resisted at this time by the rear wall of the guide 99.

From an inspection of Fig. 3 it will be understood that those portions of the levers or stop devices 27 which constitute the denominational stops 30 are arranged at letter space intervals in the usual manner for denominational selection. The lower end portions of these levers 27, however, are fanned to effect a wider separation thereof, as indicated in Fig. 4. In the present instance the lower ends of the levers 27 may be assumed to be separated at, say, four letter space distances apart. These levers are received at their lower end portions in guide slots 101 in the supporting plate 56; said slots extending fore and aft of the machine to guide the lower ends of the levers 27 in the pivotal movement of said levers. The plate 56 thus constitutes resisting means to prevent a lateral deflection of the levers when the tabulator stop 94 is brought into co-operation therewith. The lower engaging end portions of these levers are adapted to be moved rearwardly into the path of the traveling stop 94 and such engaging or arresting portions of the levers may be regarded as stops, so that the levers constitute individually operable key controlled column selecting stops and also constitute denominational stops.

From the foregoing description it will be understood that a depression of any of the tabulator keys 19 is effective to turn the cor-

responding lever 27 on its pivot 28, and at the same time to effect a release of the carriage in the manner hereinbefore described. The pivotal movement of the lever 27 thus effected not only moves the denominational stop 30, formed as a part thereof, into the path of the column stops 12 on the carriage, but also moves the arresting portion at the lower end of the lever into the path of the traveling stop 94. The construction and arrangement of the parts are such that the column stops 12 are grouped at one end portion of, say, one-half of the column stop bar so that they are effective for coöperation with the denominational stops at one portion only in the travel of the carriage; whereas the traveling stop 94 is not moved to a position where the column selecting stops are coöperative therewith until the carriage has reached another portion of its travel, where the denominational stops are no longer effective to coöperate with the column stops 12, all as will hereinafter more clearly appear. It will thus be understood that at a given portion of the travel of the carriage, say, at the first half of its travel, an actuation of any of the tabulator keys 19 is effective to denominational select in the various columnar fields determined by the adjustment of the column stops 12, and that during, say, the second half of the travel of the carriage the column stops 12 are moved with the carriage beyond a position where the denominational stops can co-act therewith. At this time, however, the traveling stop 94 has been brought to a position (by the geared connections between the carriage and said traveling stop) where an actuation of any of the tabulator keys is effective to interpose the lower end of the associated stop lever 27 in the path of the traveling stop 94, thus arresting the carriage through the coöperation of the stop lever and the traveling stop 94 in any one of several columnar fields determined by the particular tabulator key which has been actuated.

In order that the operator may at all times know whether the tabulator keys are effective for denominational or for column selecting work, I have provided a tabulator indicator and automatically actuated means by which said indicator may be shifted to bring one or another of two series of tabulator indices into view, depending on whether the keys are operative for denominational selection or for column selection. Thus from an inspection of Figs. 1 and 6, it will be observed that the front plate 102 is provided with an inclined portion 103 slotted transversely of the machine, as indicated at 104, to provide an elongated sight opening through which the tabulator indices on a suitable indicator may be displayed to the view of the operator. A scale or index plate 105, which is shown in detail

in Fig. 12, comprises in the present instance two series 106, 107 of index numerals, either of which series may be brought into register with the sight opening 104, the other series at this time being hidden from the operator's view beneath the body portion of the plate 103. The scale plate 105 is received in a sheet metal carrier 108 which is turned over at its top and bottom edges, as indicated at 109, to receive the scale plate 105 and detachably hold the latter in place. The carrier 108 is supported at its ends on levers 110 pivoted at 111 to the base of the machine and extending downwardly and rearwardly from their pivots. One of these levers is connected at its rear end to a link 112 which in turn is detachably connected at its rear end to a lever 113 of the first order. This lever 113 is pivotally mounted on the supporting plate 56 by a headed shouldered screw pivot 114, the shoulder of which is adapted to bear against a disk 115. Interposed between the disk 115 and the supporting plate 56 is a leaf spring 116 which is bent to form a connecting portion 90 at one end, as indicated at 117 in Fig. 4. The screw 114 passes through the connecting portion formed at the bent end of the spring and when the screw is tightened the end 117 of the spring is securely clamped between the disk and the supporting plate, although the lever 113 is loosely mounted to turn on the pivot screw between the head thereof and the disk 115. The free end of the spring 116 is bent to form an engaging portion 118 which, coöperates with the teeth 119 of a wheel 120 to provide a spring detent for the wheel, as will hereinafter more clearly appear. The wheel 120 is mounted on a headed shouldered pivot screw 121 which is received at its threaded end in a tapped opening in the supporting plate. A headed screw 122 projects laterally from the wheel 120 and the stem of the screw is received in a slot 123 formed in the lever 113 at the inner end portion thereof. The wheel 120 is shown in the present instance provided with six teeth and it is normally positioned, as indicated in Fig. 4, with one of said teeth in the path of the traveling stop 94. During the movement of the carriage from right to left the tabulator stop 94 will be moved in the direction of the arrow in Fig. 4, thereby bringing the stop into engagement with the rearmost tooth of the wheel 120. This effects a turning of the wheel a single tooth space distance during the movement of the stop past the wheel. This movement of the wheel is effected against the pressure of the spring detent 116 and the turning movement 125 of the wheel transmits its movement to the lever 113, thereby shifting the outer end of said lever toward the front of the machine. This movement is effective to turn the lever 110 to which the link is connected in order 130

to throw the carrier 108 upwardly and rearwardly, thereby moving the series of indices 106 on the indicator rearwardly out of register with the sight opening 104 and 5 bringing the indices 107 into register with said opening.

It will be understood that the indices contained between adjacent dividing lines 124 are adapted to register with one of the 10 tabulator keys 19 so as to constitute an indicator therefor. When the indices 106, for example, are at the sight opening the indices between each pair of adjacent dividing lines 124 will register with one of the keys. As 15 the parts are arranged in the present instance, and assuming the carriage is at the limit of its travel to the right, the denominational indices 106 will be exposed at the sight opening and the indices within each 20 space on the scale will be associated with the corresponding key which they are intended to designate. Thus the decimal point will be arranged just in the rear of the first tabulator key to the left, whereas the 25 numeral "1", indicating the units, will be in the rear of the second key and so on. When, however, the carriage reaches about midway in the travel thereof the column stops will pass beyond a position where the denominational 30 stops are co-operative therewith and the traveling tabulator stop 94 will be brought into co-operation with the wheel 120 to turn it one step, or the distance between two teeth of the wheel. The effect of this 35 movement is to actuate the lever 113, thereby shifting the indicator to bring the series of column selecting indices 107 into register with the sight opening and into register with the respective tabulator keys which the 40 indices are intended to designate. As soon as the wheel 120 has been turned in the manner described, the stop 94 is in a position to co-act with the lower ends of any of the levers 27 which may be projected to operative 45 position. If, for example, the fourth tabulator key from the left be actuated, the lower end of the corresponding lever 27 will be moved into the path of the traveling stop 94 and the carriage will be released. As 50 the carriage moves to the left the traveling stop 94 will be moved to the right until it has been arrested by the fourth lever 27, counting from the left, the stop passing the first three levers 27 without being obstructed 55 in its movement. The carriage will be arrested therefore in the fourth columnar field determined by the actuation of the fourth tabulator key. A release of the depressed tabulator key reestablishes operative 60 connection between the carriage and its escape- 65 ment mechanism, the operator proceeds to write in the fourth column and when this is completed a tabulating operation may be effected to carry the carriage to the proper 70 position to write in the next selected column.

nar field. During the return of the carriage to the right to begin a new line of writing the traveling stop 94 will engage the rear tooth of the wheel 120, thus turning the wheel back to the position it previously occupied and transmitting a corresponding movement to the lever 113, the link 112 and carrier 108 to bring the uppermost or denominational indices into register with the 75 sight opening. Thus the indicator is again in position to co-operate with the tabulator keys to properly designate said keys for denominational work which occurs at the first portion of the travel of the carriage.

A clearer understanding of the invention 80 and the purposes to be obtained thereby may be arrived at by considering the operation of the parts in connection with a blank of a specific character to be filled in with the aid of the tabulating mechanism, it being understood that various forms of blanks may be employed in connection with the mechanism but that the parts in the present instance are constructed, arranged and adjusted for use with a blank form such as is indicated, for example, at "A" in Fig. 3. In this form there are provided six columns in which the "manufacturer's" number, "style" of the goods, a "special" number applied to the goods, the quantity thereof, a "description" of the goods and the date of "delivery" thereof may be written. These columns are indicated at "a", "b", "c", "d", "e" and "f". The column stops 12 having been adjusted as indicated in Fig. 3 90 to correspond to the positions of the columns where the items are to appear, the stop 94 having been properly adjusted, and the operator having moved the carriage to the right, will proceed at once to write the manufacturer's number as "567" in the first column *a*. An actuation of the decimal key, (the same being indicated by the decimal mark on the indicator) will bring the carriage to a position where the operator may proceed to write the word "French", or such other inscription as is to appear, in the second column *b*. The operator may then depress the tens of thousands key indicated by the index numeral "10,000" opposite the 100 corresponding key. This enables the operator to write the "special" number "54635" in the third column *c*. An operation of the tens key, indicated by its appropriate index mark, is effective to arrest the carriage to enable the operator to write the designation "20" under the heading "Dozens" in the fourth column *d*. An actuation of the decimal key will arrest the carriage in the position to fill in the proper inscription in the fifth column *e* under the heading "Description". In the present instance the term "underwear" describes the class of goods. After this term has been filled in the operator may depress the decimal key to enable 110 115 120 125 130

the carriage to be arrested in position to write the date under the heading of "Delivery". This in the present instance is indicated in the double column *f* as "12 Dec. 5 24", meaning thereby that the delivery is to be made by the 24th day of December, 1912. In the movement of the carriage during the process of writing the date in the double column *f* under "Delivery", an automatic 10 actuation of the tabulator indicator will be effected, and at the time of completing the writing of the date the first five column stops 12 will be carried beyond the denominational stops and the traveling stop 94 15 will have passed the wheel 120 and be in a position to coöperate with any of the levers 27 which may be actuated, so that the parts are now in position for column selecting work. However, I have provided a sixth 20 column stop 12^a at the right-hand end of a series of column stops 12, and which column stop 12^a is in the nature of a safety stop. The purpose of this stop is to insure a proper change of the automatically actuated tabulator indicator so as to be assured 25 that the column selecting indices will be presented to the view of the operator before the tabulator keys can be operated for column selection. If the date be of an extent 30 such as that indicated in the drawing, then the automatically operated indicator will be properly actuated before the completion of the date and the tabulator indicator will expose the column selecting indices before 35 the writing of the date is finished. If, however, the date should occupy less space than that indicated in the drawings and the operator should complete the date before the carriage has arrived at a position to effect 40 an automatic change in the tabulator indicator, then an operation of any of the first four or five tabulator keys would effect an interpositioning of the corresponding denominational stop in the path of the safety 45 stop 12^a to arrest the carriage and prevent its movement to a columnar field *g* to the printing point. This insures a change in the indicator being effected to present the column selecting indices to the view of the operator 50 before the mechanism is capable of operation for column selecting work. If the safety stop should be brought into operation in the manner specified the carriage will still be positioned in the column *f*, although 55 the tabulator indicator will be automatically changed to expose the column selecting indices. The operator may then proceed to select the desired columns *g* and fill in the requisite numbers, for example, in the desired columns under the proper headings. In the present instance the blank A contains 60 indications at the heads of the next ten columns *g* of the sizes of the articles and corresponding indices are exposed at the sight opening 104. If, for example, the or-

der is for four dozen size "18", then the second tabulator key opposite the index numeral "18" will be depressed, thereby arresting the carriage in the second column *g* where the numeral "4" may be written. If 70

the order includes three dozen size "22", 75 three dozen size "34", three dozen size "40" and ten dozen size

"32", the fourth, seventh and ninth tabulator keys from the left will be successively actuated and the numerals "3", "3" and "10" will be successively written in the respective columns determined by the actuation of said keys. It will be seen that the order contains ten dozen size "44", three

dozen size "28", three dozen size "34", 80

four dozen size "18", thus making a total of twenty dozen as inscribed in the column *d* of the blank. The line having been completed the operator returns the carriage to the right, thereby moving the traveling stop 94 in a direction opposite that indicated by the arrow in Fig. 2, thus automatically actuating the indicator to expose the denominational indices instead of the column selecting indices. The second and successive lines 95 in the blank may be filled in in a like manner.

It will be seen that during, say, the first half of the travel of the carriage in each line of writing the tabulating mechanism is operative alone for denominational selection by the coöperation of the denominational stops 30 with the column stops 12; and that at this time the denominational indices are exposed at the sight opening 104, whereas 100 during, say, the second half of the travel of the carriage the tabulator mechanism will be operative for column selection alone and will be inoperative for denominational selection. At this time the tabulator indices 105 107 which aid in column selection are exposed at the sight opening 104 adjacent to the tabulator keys 19 which are now operative for column selection.

Should the character of the blank be such 110 as to necessitate column selection at the beginning of each line of writing and denominational selection at the last portion of the travel of the carriage, this may be brought about by removing the screws 114 and 121 115 of the automatically operating index-scale shifting-means and disconnecting the link 112 from the left-hand arm 110 of the index carrier. The screws 114 and 121 may be received in corresponding tapped openings 120 in the supporting plate 56 at the opposite side of the series of levers 27, as shown in Fig. 11 of the drawings. This is in order 125 that the members 113, 120, 116 and 112 may be situated at the right-hand instead of at 130

the left-hand side of the series of stop levers 27 and the link 112 may be connected with the right-hand arm 110 instead of with the corresponding arm at the left-hand side of the machine. The effect of this change in the disposition of the parts is to maintain the lowermost indices 107 at the sight opening 104 during the first half of the travel of the carriage instead of at the last half of the travel of the carriage as in the previously described arrangement of the parts. When the parts are arranged as shown in Fig. 11, the automatic shifting of the indicator is not effected until the stop 94 has passed the series of stop levers 27 during, say, the first half of the travel of the carriage. During the first half of the travel of the carriage the operation of any of the levers 27 is effective to co-act with the stop 94 to arrest the carriage in the selected columnar field as determined by the particular tabulator key which has been actuated and which keys at this time are in the nature of column selecting keys. It will be understood that in these circumstances the column stops 12 will be situated at the right-hand end portion of the column stop bar instead of at the left-hand end portion thereof so that they will not be brought into co-operative relation with the denominational stops during the first half of the travel of the carriage. But the column stop 12 will be brought into co-operative relation with a projected denominational stop after the stop 94 has passed the stop levers 27 and has automatically effected an actuation of the index scale to bring the denominational indices 106 into view at the sight opening 104. Moreover, it will be understood that by an adjustment of the stop 94 relatively to the carriage and by an adjustment of the column stops 12 to different positions along the column stop bar, the tabulator mechanism may be arranged to provide for denominational work throughout the extent of more or less of the travel of the carriage in each line of writing; and, of course, the number of columns in which denominational work may be effected may be varied according to the number of column stops 12 employed.

I have provided means in the present instance whereby the width of each column "g" selected by the column selecting mechanism may be varied. As shown in the present instance, with the use of the sprocket wheel 73, provision is made for writing as many as four characters in each of the separate columns "g." A substitution of the larger sprocket wheel 73^a, shown in Fig. 7, for the wheel 73, makes provision for writing as many as three characters in each of the columns "g," whereas a substitution of the smaller sprocket wheel 73^b, shown in Fig. 9, for the wheel 73, provides for writing as many as five characters in each of the

columns "g." These wheels, as previously pointed out, may be substituted one for another by the means shown in Fig. 10 and the corresponding change in the width of each of the columns "g" is provided for.

As hereinbefore pointed out, the eccentric 67 is effective to afford a bodily adjustment of the sprocket wheel 66 so that more or less slack may be provided in the sprocket chain 65, as may be required by the use of the different gears shown in Figs. 7, 8 and 9. Thus if the wheel 73^a be employed instead of the wheel 73 an adjustment of the eccentric 67 will be required to shift the wheel 66 nearer the axis of the wheel 64 in order to make provision for the employment of the larger sprocket wheel 73^a. After the eccentric has been rotatively adjusted to the desired position it may be secured in this position by the screw 70 so as to maintain the chain sufficiently taut to assure its proper co-operation with the various sprocket wheels.

In setting the parts according to the particular blank employed, the blank will be introduced into the machine, as shown in Fig. 3, and the carriage moved to a position where the tabulator mechanism has finished its operation as a denominational tabulator and is to begin its operation as a column selector. Thus in the present example the carriage will be moved to a position where the last written character in the column *f* under the heading "Delivery" is at the printing point. The sprocket chain will then be slackened to enable it to be disconnected from the driving wheel 73 or the clutch may be released to enable the chain to be moved independently of the carriage. The chain may then be moved longitudinally to bring the stop 94 just to the right of the first of the column stop levers 27, counting from the left in Fig. 4. The chain may then be reengaged with the sprocket wheel 73 and the eccentric positioned to maintain the chain taut, or the clutch reengaged. If desired, an index mark may be employed on the supporting plate 56 to indicate the proper position of adjustment of the stop 94. After this adjustment has been attained in the manner set forth the operator may proceed to fill in the blanks, it being understood, of course, that the column stops 12 have been previously set according to the work to be performed through the co-operation of the denominational stops 30 with said column stops 12. In setting the stop 94 in register with the index mark on the plate 56 in the manner pointed out above, it should be moved from left to right past the wheel 120 so as to shift the wheel and change the index. It will be understood that the spring detent maintains the wheel 120 in the rotative position to which it may be shifted around its pivot and is effective therefore to maintain

- the indicator in either of the two positions to which it may be shifted relatively to the sight opening 104. When the stop 94 moves from left to right past the wheel 120, said stop shifts the indicator in one direction by turning the wheel against the pressure of the detent spring 116. However, during the restoration of the carriage to begin a new line of writing the stop 94 will be moved from right to left past the wheel 120, thereby effecting a rotative movement of the wheel in the opposite direction from that which it formerly received, thus returning the indicator to its normal position.
- 15 If the operator should desire to use the construction for column selecting work alone it is merely necessary to remove the column stops 12 and the safety stops 12^a. If, on the other hand, the operator desires 20 to employ the denominational stop mechanism to the exclusion of the column selecting mechanism, then the stop 94 may be adjusted to a position relatively to the carriage where it will not be brought into coöperative 25 relation with the levers 27 or with the wheel 120 throughout the entire travel of the carriage. This may be readily done by moving the carriage to the extreme right, releasing the clutch which connects the driving wheel 30 73 with the driving shaft and moving the chain longitudinally until the stop 94 is positioned to the right of the series of stop levers 27. The clutch may then be engaged but the travel of the stop 94 during the 35 travel of the carriage will be such that it is never brought into coöperative relation with the stop levers 27 or with the wheel 120. The tabulator therefore as a column selecting mechanism will be thrown out of use 40 but will still be effective for denominational selection. A disconnection of the clutch by which the wheel 73 is connected to the driving shaft is in itself sufficient to render the mechanism inoperative as a column selector 45 and to throw the automatically actuated means for the indicator out of operation.
- It will thus be seen that provision is made for the use of the tabulator mechanism, when desired, as a mere column selector which 50 will afford a selection of any one of eleven columns under the control of the ten tabulator keys 19. These columns will occupy, when the wheel 73^b, for example, is in use, a space corresponding to 55 or more letter 55 space positions in the travel of the carriage and the parts may be arranged to begin the columnar selection at any point in the travel of the carriage, depending on the relative adjustment between the stop 94 and the carriage. If, for example, the first of the series 60 of columnar fields which may be selected with the aid of keys is to begin at "20", then the carriage will be moved to the position "20" as indicated by the carriage 65 scale. The chain will be released from con-
- trol of the driving sprocket and the stop 94 will be adjusted just to the right of the left-hand stop lever 27. The chain may then be re-connected with the driving sprocket and when the first column selecting 70 key is depressed, the carriage will be arrested to write in the first column, beginning at the point "20" on the carriage scale, it being understood, of course, that at this time the column stops 12 and the safety stop 12^a 75 have been removed from the machine. Any one of nine succeeding columns arranged five letter space distances apart may be selected with the aid of the tabulator keys 19, which at this time operate as column selecting 80 keys.
- If desired, an additional stop corresponding with the stop 94 may be employed on the driving chain, which last mentioned stop will be brought into coöperative relation 85 with the stop levers 27 after the first stop 94 has moved beyond or past said levers. By these means columns may be provided across the entire sheet and any of said columns may be selected at will. During the 90 first half of the travel of the carriage the first traveling stop 94 will co-act with any of the levers 27 which may be actuated and during the second half of the travel of the carriage the second traveling stop 94 will 95 co-act with said levers. In these circumstances the character of the indices on the index plate 105 will be modified so that both series of indices will be column designating 100 indices, one series of which will be exposed at the sight opening 104 during the first half of the travel of the carriage and the second series of which will accord with the headings of the columns which may be selected at the second half of the travel of 105 the carriage and an automatic actuation of the indicator will bring the second set of indices into view at the sight opening in the manner hereinbefore described.
- When the tabulating mechanism is to be 110 used exclusively as a denominational tabulator the stop 94 may be adjusted to a position where it will never come into contact with the wheel 120, as hereinbefore explained, or the link 112 may be disconnected 115 from the tabulator indicator so as to render the latter inoperative. In either event the tabulator indicator set for denominational work will remain indefinitely in the position to which it is set. If column selection work 120 alone is to be effected the link 112 may be disconnected from the indicator after the latter has been set to expose the column selection indices, it being understood that sufficient friction may be provided at the pivots 125 111 of the indicator to maintain it against accidental displacement in either of the positions to which it may be shifted.
- It will be understood from the foregoing 130 description that the same key controlled de-

vices 27 which are effective at one period during the travel of the carriage as denominational stop devices, are effective during another period in the travel of the carriage as column selecting stops; that the same keys which control said devices 27 act in one case as denominational selecting keys and in the other case as column selecting keys; that the tabulator indicating mechanism coöperative with said keys is automatically changed according to the purposes for which the keys are operative or effective, in one instance acting as denominational selecting keys and in the other instance as column selecting keys; that the construction is comparatively simple; that the means by which a column selection as well as a denominational selection may be effected and the means by which an automatic shifting of the tubulator indices is obtained are in the nature of attachments which may be readily applied to existing forms of typewriting machines, such as the No. 11 Remington machine, without modifying, or materially modifying, the structural features of said machines as they now exist; that the construction is such that it may be employed for various characters of tabulating work, either as a denominational tabulator or as a column selector or as a column selector at one portion of the travel of the carriage and a denominational selector at another portion of the travel of the carriage; that the construction lends itself readily to variation and arrangement of the parts in order to enable it to operate effectively in connection with various styles of tabulating work; that various changes may be made in the construction and arrangement of the parts without departing from the spirit of my invention and that some of the parts may be used without others, depending on the nature of the work to be produced.

45 What I claim as new and desire to secure by Letters Patent, is:—

1. In a typewriting machine, the combination of a carriage; and denominational and column selecting tabulating mechanism having a plurality of key controlled stops and including means by which said tabulating mechanism is necessarily operative as a denominational tabulator or as a column selector depending on the position of the carriage in its line of travel, two key controlled stops being actuated at each operation of a key.

2. In a typewriting machine, the combination of a carriage; and denominational and column selecting mechanism having a plurality of key controlled stops and including automatically operating means by which said tabulating mechanism is necessarily operative first for one character of selection and then for the other, there being twice as

many key controlled stops as there are keys to control them.

3. In a typewriting machine, the combination of a carriage; and tabulating mechanism having a plurality of selecting keys and two stops controlled by each key, said mechanism including automatically operating means by which said keys are operative at one time to control the tabulating mechanism only to obtain a denominational selection and are operative at another time to control the tabulating mechanism only for column selection.

4. In a typewriting machine, the combination of a carriage; and tabulating mechanism having a plurality of selecting keys and two stops controlled by each key, said mechanism including automatically operating means by which said keys are operative at one time to control the tabulating mechanism only to obtain a denominational selection and are operative at another time to control the tabulating mechanism only for column selection, the position of the carriage in its line of travel determining whether the keys are operative for denominational selection or for column selection.

5. In a typewriting machine, the combination of a carriage; tabulating mechanism having a plurality of selecting keys and two stops controlled by each key, said mechanism including automatically operating means by which said keys are operative at one time to control the tabulating mechanism only to obtain a denominational selection and are operative at another time to control the tabulating mechanism only for column selection, the position of the carriage in its line of travel determining whether the keys are operative for denominational selection or for column selection; and means which enable the keys during the given portion of the travel of the carriage to control the operation of the tabulating mechanism for either one character of selection or the other.

6. In a typewriting machine, the combination of a carriage; and tabulating mechanism including keys and automatically operating means by which said keys are operative at one time to control the tabulating mechanism only to obtain denominational selection and are operative at another time to control the tabulating mechanism only for column selection, said means comprising a series of column stops movable with the carriage, a tabulator stop moved by the carriage but in a different path from said column stops, and tabulator devices controlled by said keys and coöperative with said column stops and with said tabulator stop.

7. In a typewriting machine, the combination of a carriage; and tabulating mechanism including keys and automatically operating means by which said keys are opera-

- tive at one time to control the tabulating mechanism only to obtain a denominational selection and are operative at another time to control the tabulating mechanism only for column selection, the position of the carriage in its line of travel determining whether the keys are operative for denominational selection or for column selection, said means comprising a series of column stops movable with the carriage, a tabulator stop moved by the carriage but in a different path from said column stops, and tabulator devices controlled by said keys and co-operative with said column stops and with said tabulator stop, the construction and relation of the parts being such that any of said key controlled devices may be brought into co-operative relation with one of said column stops but not with said tabulator stop during one portion of the travel of the carriage and may be brought into co-operative relation with said tabulator stop but not with said column stops at another portion of the travel of the carriage.
8. In a typewriting machine, the combination of a carriage, and tabulating mechanism having a plurality of selecting keys and stops controlled thereby, and including means whereby said mechanism is operative successively a predetermined number of times in the travel of the carriage only as a denominational tabulator and is operative successively a predetermined number of times during the writing of the same line only as a column selector, there being twice as many key controlled stops as there are selecting keys to control them.
9. In a typewriting machine, the combination of a carriage; and tabulating mechanism comprising a plurality of selecting keys, two sets of stops controlled by said keys, a traveling stop with which one set only of said key controlled stops is co-operative during one portion of the travel of the carriage, and a second traveling stop with which the other set only of key controlled stops is co-operative during another portion of the travel of the carriage.
10. In a typewriting machine, the combination of a carriage; and tabulating mechanism comprising two traveling stops which are adapted to travel in opposite directions during the movement of the carriage in one direction, and key controlled stop means which co-act with said traveling stops.
11. In a typewriting machine, the combination of a carriage; and tabulating mechanism comprising two traveling stops which are adapted to travel in opposite directions during the movement of the carriage in one direction, key controlled denominational stops which co-act with one of said traveling stops, and key controlled column selecting stops which co-operate with the other of said traveling stops.
12. In a typewriting machine, the combination of a carriage; denominational and column selecting tabulating mechanism having a plurality of selecting keys and stops controlled thereby, there being twice as many key controlled stops as there are selecting keys to control them, the tabulating mechanism including means co-operative with said stops and by which the position of the carriage in its line of travel determines whether said keys shall be operative to select different columnar fields or different denominational positions; and means by which said tabulating mechanism may be rendered ineffective for one character of selection without effecting its operativeness for the other character of selection.
13. In a typewriting machine, the combination with the carriage, of column-selecting tabulating mechanism comprising an endless band, a contact-device controlled thereby, and other mechanism including carriage-arresting devices, the contact-device being movable in a straight path and its co-operation with the rest of the mechanism depending on its movement through different distances in that path.
14. In a typewriting machine, the combination with the carriage, of column-selecting denominational tabulating mechanism comprising an endless band, a contact-device controlled thereby, and other mechanism including denominational carriage-arresting means, the contact device being movable in a straight path and its co-operation with the rest of the mechanism depending on its movement through different distances in that path.
15. In a typewriting machine, the combination with the carriage, of column-selecting tabulating mechanism comprising an endless band, a contact-device controlled thereby, and other mechanism including carriage-arresting devices, the action of the band depending on the movement of the carriage, and the contact device being movable in a straight path and its co-operation with the rest of the mechanism depending on its movement through different distances in that path.
16. In a typewriting machine, the combination with the carriage, of column-selecting tabulating mechanism comprising an endless band, a contact device controlled thereby, and other mechanism including key-controlled stops, the contact device being movable in a straight path and its co-operation with the rest of the mechanism depending on its movement through different distances in that path.
17. In a typewriting machine, the combination with the carriage, of column-selecting denominational tabulating mechanism comprising an endless band, a contact-device controlled thereby, and other mechanism in-

cluding key controlled column-selecting and denominational stops, the contact device being movable in a straight path and its coöperation with the rest of the mechanism 5 depending on its movement through different distances in that path.

18. In a typewriting machine, the combination with the carriage, of column-selecting tabulating mechanism comprising an endless band, a contact-device controlled thereby, and other mechanism including a series of stops arranged in a row, the contact-device being movable in a straight path from side to side of said series of stops.
- 15 19. In a typewriting machine, the combination of a carriage; and tabulating mechanism comprising an endless band, wheels around which said band passes, said band being movable concurrently with the carriage, and means by which an adjustment of 20 said band relatively to the carriage may be effected.

20. In a typewriting machine, the combination of a carriage; and tabulating mechanism comprising wheels operatively connected to the carriage, an endless band which passes around said wheels and which is movable concurrently with the carriage, and means by which an adjustment of said band 25 around said wheels and independently of the movement of the carriage may be effected.

21. In a typewriting machine, the combination of a carriage; and tabulating mechanism comprising wheels operatively connected to the carriage, an endless band which passes around said wheels and which is movable concurrently with the carriage, means by which an adjustment of said band around 30 said wheels and independently of the movement of the carriage may be effected, a contact device controlled by said band, and key controlled tabulator stop devices.

22. In a typewriting machine, the combination with the carriage, of column-selecting tabulating mechanism comprising an endless sprocket-chain, sprocket-wheels that carry the chain, operative connections between one of the sprocket-wheels and the 45 carriage, and a contact-device controlled by the chain and movable in a straight path, its coöperation with the rest of the mechanism depending on its movement through different distances in that path.

55 23. In a typewriting machine, the combination of a carriage; and tabulating mechanism comprising an endless sprocket chain, sprocket wheels around which said chain passes, operative connections between said 60 chain and the carriage, means for affording an adjustment of said chain around the axes of said sprocket wheels and independently of the movement of the carriage, and a contact device controlled by said chain.

24. In a typewriting machine, the combination of a carriage; and tabulating mechanism comprising an endless sprocket chain, sprocket wheels around which said chain passes, operative connections between said chain and the carriage, a contact device controlled by said chain, a series of column stops, and key controlled tabulator stops.

25. In a typewriting machine, the combination of a carriage; and tabulating mechanism comprising an endless sprocket chain, 75 sprocket wheels around which said chain passes, operative connections between said chain and the carriage, means for affording an adjustment of said chain around the axes of said sprocket wheels and independently 80 of the movement of the carriage, a contact device controlled by said chain, a series of adjustable column stops, and a series of key controlled tabulator stops.

26. In a typewriting machine, the combination of a carriage; and tabulating mechanism comprising an endless sprocket chain which extends longitudinally in the general direction of the travel of the carriage, operative connections between said carriage and 90 chain to cause the chain to move during the travel of the carriage, and a contact device controlled by said chain.

27. In a typewriting machine, the combination with the carriage, of column-selecting 95 denominational tabulating mechanism comprising an endless band, a contact-device controlled thereby, and other mechanism including column - stops and denominational stops.

28. In a typewriting machine, the combination of a carriage, and tabulating mechanism including keys and automatically operating means by which said keys are operated at one time to control the tabulating 105 mechanism only to obtain a denominational selection and are operative at another time to control the tabulating mechanism only for column selection, said means comprising a series of column stops movable with 110 the carriage, a tabulator stop moved by the carriage but in a different path from said column stops, and tabulator devices controlled by said keys and coöperative with said column stops and with said tabulator 115 stop, the tabulating mechanism also including means to render it convertible into a denominational selector alone and into a column selector alone.

29. In a typewriting machine, the combination of a carriage, and tabulating mechanism including keys and automatically operating means by which said keys are operative at one time to control the tabulating 120 mechanism only to obtain a denominational selection and are operative at another time to control the tabulating mechanism only for column selection, the po- 125

sition of the carriage in its line of travel determining whether the keys are operative for denominational selection or for column selection, said means comprising a 5 series of column stops movable with the carriage, a tabulator stop moved by the carriage but in a different path from said column stops, and tabulator devices controlled by said keys and coöperative with said column 10 stops and with said tabulator stop, the construction and relation of the parts being such that any of said key controlled devices may be brought into coöperative relation with one of said column stops but not with 15 said tabulator stop during one portion of the travel of the carriage and may be brought into coöperative relation with said tabulator stop but not with said column stops at another portion of the travel of the carriage, 20 and the tabulating mechanism also including means by which said key controlled tabulator devices are rendered coöperative exclusively either with said column stops or with said tabulator stop, so that the tabulating mechanism may be converted into a 25 denominational selector alone and into a column selector alone.

30. In a typewriting machine, the combination of a carriage, two stop carriers, a stop carried by each carrier, and key controlled means which are coöperative with said stops to arrest the carriage, said key controlled means being coöperative with one of said stops at the first portion only of the 35 travel of the carriage and coöperative with the other stop only during the last portion of the travel of the carriage.

31. In a typewriting machine, the combination of a carriage, two stop carriers one 40 carried by the carriage and the other separate from but connected to be moved by the carriage, a stop carried by each of said carriers, and key controlled means coöperative with one or the other of said stops depending 45 on the position of the carriage in its line of travel.

32. In a typewriting machine, the combination of a carriage, two traveling stops which are separated and have separate fixed 50 paths of movement, the movement of each depending on that of the carriage, and a key controlled stop that is moved at each operation into the paths both of said traveling stops but is coöperative therewith at different 55 times by reason of the difference in location of said traveling stops relatively to each other.

33. In a typewriting machine, the combination of a carriage, two traveling stops 60 which are separated and have separate fixed paths of movement, the movement of each depending on that of the carriage, and a series of key controlled stops each movable at an operation thereof into the paths of both

of said traveling stops but coöperative therewith at different times by reason of the difference in location of the traveling stops relatively to each other. 65

34. In a typewriting machine, the combination of a carriage, key controlled tabulator stops which are spaced apart at given intervals, key controlled stops which are spaced apart at different intervals from said first mentioned stops, a traveling stop which moves in one path and with which said first 70 mentioned key controlled stops coöperate, and a second traveling stop which travels in a different path from the other traveling stop and with which said second mentioned key controlled stops coöperate. 75

35. In a typewriting machine, the combination of a carriage, key controlled tabulator stops which are spaced apart at given intervals, key controlled stops which are spaced apart at different intervals from said 80 first mentioned stops, a traveling stop which moves in one path and with which said first mentioned key controlled stops coöperate, and a second traveling stop which travels in a different path from the other traveling stop and with which said second mentioned key controlled stops coöperate, the keys which control said first mentioned stops also controlling the second key controlled stops. 85

36. In a typewriting machine, the combination of a carriage, a series of key controlled devices spaced apart differently at different portions thereof, stops which travel in different paths, a stop traveling in one path coöperating with those portions of 90 said key controlled devices which have one character of spacing, and another stop traveling in a different path coöperating with those portions of said devices which have a different character of spacing. 95

37. In a typewriting machine, the combination of a carriage, key controlled stop devices spaced apart at one portion thereof at letter space intervals and spaced apart at other portions thereof at a plurality of 100 letter space intervals, a traveling stop coöperative with those portions of said devices which have one character of spacing, and a second traveling stop which coöperates with those portions of said devices which are 105 differently spaced. 110

38. In a typewriting machine, the combination of a carriage, key controlled stop, which are spaced apart at letter space intervals and constitute denominational stops, 115 key controlled stops which are spaced apart at a plurality of letter space intervals and constitute column selecting stops, a traveling stop with which the denominational stops coöperate, and a second traveling stop which travels in a different path from said first mentioned traveling stop and with which the column stops are coöperative. 120 125

39. In a typewriting machine, the combination of a carriage, key controlled stops which are spaced apart at letter space intervals and constitute denominational stops, 5 key controlled stops which are spaced apart at a plurality of letter space intervals and constitute column selecting stops, a traveling stop with which the denominational stops coöperate, and a second traveling stop 10 which travels in a different path from said first mentioned traveling stop and with which the column stops are coöoperative, the keys which control the denominational stops also controlling the column selecting stops. 15 40. In a typewriting machine, the combination of a carriage, key controlled stops which are spaced apart at letter space intervals and constitute denominational stops, key controlled stops which are spaced apart 20 at a plurality of letter space intervals and constitute column selecting stops, a traveling stop with which the denominational stops coöperate, and a second traveling stop which travels in a different path from said 25 first mentioned traveling stop and with which the column stops are coöoperative, the relative arrangement of the two traveling stops being such that one of them will be brought into position where the denominational stops may coöperate therewith at one 30 portion of the travel of the carriage and the other traveling stop will be brought to a position where the column selecting stops may coöperate therewith at another portion 35 of the travel of the carriage.

41. In a typewriting machine, the combination of a carriage, a series of key controlled levers pivoted intermediate the ends thereof, a traveling tabulator stop having a 40 path of movement transversely of said levers and at one side of the pivotal centers thereof and with which said levers are coöoperative to arrest the carriage, and a second traveling tabulator stop having a path of movement transversely of said levers and at the 45 opposite side of the pivotal centers thereof and with which said levers are coöoperative to arrest the carriage.

42. In a typewriting machine, the combination of a carriage, a series of key controlled levers pivoted intermediate the ends thereof, the spacing between said levers at one side of the pivotal centers thereof being different from what it is at the opposite side 50 of the pivotal centers of said levers, a traveling tabulator stop having a path of movement transversely of said levers and at one side of the pivotal centers thereof and with which said levers are coöoperative to arrest 55 the carriage, and a second traveling tabulator stop having a path of movement transversely of said levers and at the opposite side of the pivotal centers thereof and with which said levers are coöoperative to arrest 60 the carriage, and a second traveling tabulator stop having a path of movement transversely of said levers and at the opposite side of the pivotal centers thereof and with which said levers are coöoperative to arrest 65 the carriage.

43. In a typewriting machine, the combination of a carriage, a series of key controlled levers pivoted intermediate the ends thereof, said levers at one side of the pivotal centers thereof being spaced apart at 70 letter space intervals to form denominational stops, the levers at the opposite side of the pivotal centers being spaced apart at a plurality of letter space intervals to form column selecting stops, a plurality of 75 traveling stops with each of which the denominational stops are coöoperative, and a single traveling stop with which said column selecting stops are coöoperative.

44. In a typewriting machine, the combination of a carriage, a series of key controlled levers pivoted intermediate the ends thereof, a traveling tabulator stop having a path of movement transversely of said levers and at one side of the pivotal centers 80 thereof and with which said levers are coöoperative to arrest the carriage, a second traveling tabulator stop having a path of movement transversely of said levers and at the opposite side of the pivotal centers 85 thereof and with which said levers are coöoperative to arrest the carriage, and carriage releasing means which are operated to release the carriage when any of said key controlled levers is actuated. 90 95

45. In a typewriting machine, the combination of a carriage, a series of key controlled levers pivoted intermediate the ends thereof, said levers at one side of the pivotal centers thereof being spaced apart at letter 100 space intervals to form denominational stops, the levers at the opposite side of the pivotal centers being spaced apart at a plurality of letter space intervals to form column selecting stops, a plurality of traveling stops with each of which the denominational stops are coöoperative, a single traveling stop with which said column selecting stops are coöoperative, and carriage 105 releasing means which are operated to release the carriage when any of said key controlled levers is actuated. 110 115

46. In a typewriting machine, the combination of a carriage, a column stop bar carried thereby, a series of column stops carried by said stop bar, a series of key controlled denominational stop carrying levers, the denominational stops being moved by said levers into coöoperative relation with said column stops, and a traveling tabulator stop which is moved by the carriage and travels in a different path from said column stops and into the path of which each of said levers is adapted to be moved. 120 125

47. In a typewriting machine, the combination of a carriage, a column stop bar carried thereby, a series of column stops carried by said stop bar, a series of key controlled denominational stop carrying levers, the denominational stops being moved by 130

5 said levers into coöperative relation with said column stops, a traveling tabulator stop which is moved by the carriage and travels in a different path from said column stops and into the path of which each of said levers is adapted to be moved, means which afford an adjustment of the column stops along said bar, and means which afford an adjustment of said traveling tabulator stop 10 relatively to the carriage.

48. In a typewriting machine, the combination of a carriage, a column stop bar carried thereby, a series of column stops carried by said stop bar, a series of key controlled denominational stop carrying levers, the denominational stops being moved by said levers into coöperative relation with said column stops, an endless band driven by the carriage, and a tabulator stop carried by 20 said endless band and with which said levers are coöperative to arrest the carriage.

49. In a typewriting machine, the combination of a carriage, a column stop bar carried thereby, a series of column stops carried by said stop bar, a series of key controlled denominational stop carrying levers, the denominational stops being moved by said levers into coöperative relation with said column stops, means for affording an 30 adjustment of said column stops along said bar, an endless band driven by the carriage, a tabulator stop carried by said band and with which said levers are adapted to coöperate to arrest the carriage, and means for affording a longitudinal adjustment of said band to vary the position of the stop carried thereby relatively to the carriage.

50. In a typewriting machine, the combination of a carriage, two stop carriers, a stop 40 carried by each carrier, and key controlled means which are coöperative with said stops to arrest the carriage, said key controlled means being coöperative with one of said stops at the first portion only of the travel 45 of the carriage and coöperative with the other stop only during the last portion of the travel of the carriage, and the construction being such that one of said stops may be rendered inoperative to coöperate with 50 said key controlled means.

51. In a typewriting machine, the combination of a carriage, two stop carriers one carried by the carriage and the other separate from but connected to be moved by the 55 carriage, a stop carried by each of said carriers, and key controlled means coöperative with one or the other of said stops depending on the position of the carriage in its line of travel, the construction being such that one of said stops may be rendered inoperative to coöperate with said key controlled means.

52. In a typewriting machine, the combination of a carriage, two traveling stops 60 which are separated and have separate fixed

paths of movement, the movement of each depending on that of the carriage, and a key controlled stop that is moved at each operation into the paths of both of said traveling stops but is coöperative therewith at different times by reason of the difference in location of said traveling stops relatively to each other, the construction being such that one of said traveling stops may be rendered inoperative to coöperate with said 75 key controlled stop.

53. In a typewriting machine, the combination of a carriage, two traveling stops which are separated and have separate fixed paths of movement, the movement of each 80 depending on that of the carriage, and a series of key controlled stops each movable at an operation thereof into the paths of both of said traveling stops but coöperative therewith at different times by reason of the difference in location of the traveling stops relatively to each other, the construction being such that either of said traveling stops may be rendered inoperative to coöperate with said key controlled stops. 85

54. In a typewriting machine, the combination of a carriage, key controlled tabulator stops which are spaced apart at given intervals, key controlled stops which are spaced apart at different intervals from said 90 first mentioned stops, a traveling stop which moves in one path and with which said first mentioned key controlled stops coöperate, and a second traveling stop which travels in a different path from the other traveling 95 stop and with which said second mentioned key controlled stops coöperate, the construction being such that one of said traveling stops may be rendered inoperative to coöperate with its key controlled stops. 100

55. In a typewriting machine, the combination of a carriage, key controlled tabulator stops which are spaced apart at given intervals, key controlled stops which are spaced apart at different intervals from said 110 first mentioned stops, a traveling stop which moves in one path and with which said first mentioned key controlled stops coöperate, and a second traveling stop which travels in a different path from the other traveling stop and with which said second mentioned key controlled stops coöperate, the keys which control said first mentioned stops also controlling the second key controlled stops, and the construction being such that either 120 of said traveling stops may be rendered inoperative to coöperate with said key controlled stops. 115

56. In a typewriting machine, the combination of a carriage, a series of key controlled devices spaced apart differently at different portions thereof, and stops which travel in different paths, a stop traveling 125 in one path coöperating with those portions of said key controlled devices which have 130

one character of spacing, another stop traveling in a different path coöperating with those portions of said devices which have a different character of spacing, and the construction being such that one of said traveling stops may be rendered inoperative to coöperate with said key controlled devices.

57. In a typewriting machine, the combination of a carriage, key controlled stops 10 which are spaced apart at letter space intervals and constitute denominational stops, key controlled stops which are spaced apart at a plurality of letter space intervals and constitute column selecting stops, a traveling 15 stop with which the denominational stops coöperate, and a second traveling stop which travels in a different path from said first mentioned traveling stop and with which the column selecting stops are coöperative, the construction being such that either of said traveling stops may be rendered inoperative to coöperate with its key controlled stops.

58. In a typewriting machine, the combination of a carriage, key controlled stops 25 which are spaced apart at letter space intervals and constitute denominational stops, key controlled stops which are spaced apart at a plurality of letter space intervals and 30 constitute column selecting stops, a traveling stop with which the denominational stops coöperate, and a second traveling stop which travels in a different path from said first mentioned traveling stop and with 35 which the column selecting stops are coöperative, the relative arrangement of the two traveling stops being such that one of them will be brought into position where the denominational stops may coöperate there- 40 with at one portion of the travel of the carriage and the other traveling stop will be brought to a position where the column selecting stops may coöperate therewith at another portion of the travel of the carriage, 45 and the construction being such that either of said traveling stops may be rendered inoperative to coöperate with its key controlled coöperative stops.

59. In a typewriting machine, the combination of a carriage, a series of key controlled levers pivoted intermediate the ends thereof, a traveling tabulator stop having a path of movement transversely of said levers and at one side of the pivotal centers 55 thereof and with which said levers are coöperative to arrest the carriage, and a second traveling tabulator stop having a path of movement transversely of said levers and at the opposite side of the pivotal centers 60 thereof and with which said levers are coöperative to arrest the carriage, the construction being such that one of said traveling stops may be rendered inoperative to coöperate with said levers.

60. In a typewriting machine, the combination of a carriage, a series of key controlled levers pivoted intermediate the ends thereof, said levers at one side of the pivotal centers thereof being spaced apart at letter space intervals to form denominational stops, the levers at the opposite side of the pivotal centers thereof being spaced apart at a plurality of letter space intervals to form column selecting stops, a plurality of traveling stops with each of which the denominational stops are coöperative, and a single traveling stop with which said column selecting stops are coöperative, the construction being such that certain of said traveling stops may be rendered inoperative.

61. In a typewriting machine, the combination of a carriage, an endless band driven by the carriage, a tabulator traveling stop carried by said band, and key controlled tabulator stop mechanism coöperative with said first mentioned stop.

62. In a typewriting machine, the combination of a carriage, an endless driving band, means which enable any one of a series of interchangeable gears of different 90 sizes to be employed between the carriage and said band to drive the latter from the carriage, a tabulator stop carried by said band, and key controlled tabulator stop mechanism coöperative with said first mentioned stop.

63. In a typewriting machine, the combination of a carriage, an endless band driven by the carriage, a traveling tabulator stop carried by said band, and a series of key controlled tabulator stops coöperative with said first mentioned stop.

64. In a typewriting machine, the combination of a carriage, an endless band driven by the carriage, a tabulator stop carried by said band, and a series of key controlled independently operable column selecting stops which coöperate with said first mentioned stop, the spacing between said column selecting stops regulating the spacing of 105 columns.

65. In a typewriting machine, the combination of a carriage, a stop carrier separate from but moved by the carriage, a stop carried by said carrier, intermediate driving connections between the carriage and said carrier, said connections being constructed to allow the velocity ratio between the carrier and the carriage to be changed at will, and a key actuated tabulator stop coöperative with the stop on said carrier.

66. In a typewriting machine, the combination of a carriage, a stop carrier separate from but moved by the carriage, a traveling stop carried by said carrier, intermediate driving connections between the carriage and said carrier, said connections being constructed to allow the velocity ratio between

the carrier and the carriage to be changed at will, and a series of key controlled independently operable tabulator stops coöperative with said first mentioned stop.

5 67. In a typewriting machine, the combination of a carriage, a stop carrier separate from but moved by the carriage, a traveling stop carried by said carrier, intermediate driving connections between the carriage and said carrier, said connections being constructed to allow the velocity ratio between the carrier and the carriage to be changed at will, a series of key-controlled independently operable column selecting stops coöperative with said first mentioned stop, said column selecting stops being arranged at unvariable distances apart and the variation in spacing of the columns being controlled by the change in velocity ratio between the carriage and said carrier.

10 68. In a typewriting machine, the combination of a carriage, an endless band driven by the carriage, a tabulator traveling stop carried by said band, and key controlled tabulator stop mechanism coöperative with said first mentioned stop, the construction being such that said traveling stop may be rendered inoperative to coöperate with said key controlled stop.

15 69. In a typewriting machine, the combination of a carriage, an endless band driven by the carriage, a traveling tabulator stop carried by said band, and a series of key controlled tabulator stops coöperative with said first mentioned stop, the construction being such that said traveling stop may be rendered inoperative to coöperate with any of said key controlled stops.

20 70. In a typewriting machine, the combination of a carriage, a stop carrier separate from but moved by the carriage, a traveling stop carried by said carrier, intermediate driving connections between the carriage and said carrier, said connections being constructed to allow the velocity ratio between the carrier and the carriage to be changed at will, and a series of key controlled independently operable column selecting stops coöperative with said first mentioned stop, said column selecting stops being arranged at unvariable distances apart and the variation in spacing of the columns being controlled by the change in velocity ratio between the carriage and said carrier, the construction being such that said traveling stop is rendered inoperative to coöperate with any of said key controlled stops.

25 71. In a typewriting machine, the combination of an endless band driven by the carriage, a tabulator stop carried by said band, a coöperative tabulator stop, and a guide coöperative with said band to prevent it from flexing when said stops are brought into engagement.

72. In a typewriting machine, the combination of an endless band driven by the carriage, a tabulator stop carried by said band, a coöperative tabulator stop, and a guide coöperative with said band to prevent it from flexing when said stops are brought into engagement, said guide being slotted to enable the stop carried by said band to pass through the guide.

73. In a typewriting machine, the combination of a carriage, a sprocket chain driven by said carriage, a tabulator stop carried by said sprocket chain, a coöperative tabulator stop, and a guide for said sprocket chain to prevent the chain from being flexed when said stops are brought into engagement.

74. In a typewriting machine, the combination of a carriage, a sprocket wheel which is driven by said carriage, a sprocket chain which meshes with said sprocket wheel, a guide which prevents the chain from moving out of mesh with said wheel, a tabulator stop carried by said chain, and a coöperative tabulator stop.

75. In a typewriting machine, the combination of a carriage, a sprocket wheel which is driven by said carriage, a sprocket chain which meshes with said sprocket wheel, a guide which prevents the chain from moving out of mesh with said wheel, a tabulator stop carried by said chain, means for enabling the guide to be moved to inoperative position to afford a disengagement of the chain from said sprocket wheel, and a coöperative tabulator stop.

76. In a typewriting machine, the combination of a carriage, a sprocket wheel which is driven by said carriage, a sprocket chain which meshes with said sprocket wheel, a guide which prevents the chain from moving out of mesh with said wheel, a tabulator stop carried by said chain, means for affording an adjustment of said guide to different positions and for securing it in any position to which it may be adjusted, and a coöperative tabulator stop.

77. In a typewriting machine, the combination of a carriage, a sprocket wheel which is driven by said carriage, a sprocket chain which meshes with said sprocket wheel, means for affording a removal of said sprocket wheel and for securing a substitute sprocket wheel of a different size in place of said first mentioned sprocket wheel, a guide which prevents the chain from moving out of mesh with said wheel, a tabulator stop carried by said chain, means for affording an adjustment of said guide to different positions and for securing it in any position to which it may be adjusted to properly coöperate with the chain irrespective of the size of the sprocket wheel employed, and a coöperative tabulator stop.

78. In a typewriting machine, the combi-

- 5 nation of a carriage, a traveling tabulator stop connected to be moved by the carriage but at a different rate of speed from the carriage, and a key controlled coöperative tab-
5 ular stop. 70
- 10 79. In a typewriting machine, the combination of a carriage, a traveling tabulator stop connected to be moved by the carriage but at a different rate of speed from the carriage, the construction being such as to allow the rate of speed at which the traveling stop moves relatively to the carriage to be changed, and a key controlled coöperative tabulator stop. 75
- 15 80. In a type writing machine, the combination of a carriage, a traveling tabulator stop, reduction gearing between said carriage and said traveling stop to move the latter by a movement of the carriage but at a 80 lower rate of speed, and a key controlled tabulator stop coöperative with said traveling stop. 85
- 20 81. In a typewriting machine, the combination of a carriage, a traveling tabulator stop, reduction gearing between said carriage and said traveling stop to move the latter by a movement of the carriage but at a 90 slower rate of speed, said reduction gearing including a removable gear which may be replaced by a gear of a different size so as to vary the speed of the traveling stop relatively to the carriage, and a key controlled tabulator stop coöperative with said traveling stop. 95
- 25 82. In a typewriting machine, the combination of a carriage, a traveling tabulator stop connected to be moved by the carriage but at a different rate of speed from the carriage, and a series of independently oper- 100 able key controlled stops that may be moved into coöperative relation with said traveling stop. 105
- 30 83. In a typewriting machine, the combination of a carriage, a traveling tabulator stop connected to be moved by the carriage but at a different rate of speed from the carriage, and a series of independently operable key controlled stops that may be moved into coöperative relation with said traveling stop, 110 said key controlled stops being separated a plurality of letter space distances apart. 115
- 35 84. In a typewriting machine, the combination of a carriage, a traveling tabulator stop connected to be moved by the carriage but at a different rate of speed from the carriage, the construction being such as to allow the rate of speed at which the traveling stop moves relatively to the carriage to be changed, and a series of independently operable key controlled stops that may be moved into coöperative relation with said traveling stop, said key controlled stops being separated a plurality of letter space distances apart. 120
- 40 85. In a typewriting machine, the combi- 125 nation of a carriage, a traveling tabulator stop, reduction gearing between said carriage and said traveling stop to move the latter by a movement of the carriage but at a slower rate of speed, said reduction gearing including a removable gear which may be replaced by a gear of a different size so as to vary the speed of the traveling stop relatively to the carriage, a series of column stops carried by the carriage, and a key controlled tabulator stop device coöperative with said column stops and also with said traveling stop, the construction being such that certain of said 130

stops may be rendered inoperative to co-operate with said key controlled tabulator stop device.

91. In a typewriting machine, the combination of a carriage, a traveling tabulator stop, reduction gearing between said carriage and said traveling stop to move the latter by a movement of the carriage but at a slower rate of speed, a series of column stops carried by the carriage, and a series of independently operable stop devices each of which is cooperative with said column stops and also with said traveling stop, the construction being such that certain of said stops may be rendered inoperative to co-operate with any of said independently operable stop devices.

92. In a typewriting machine, the combination of a carriage, tabulator indicating mechanism, and automatically operating means for changing said indicating means.

93. In a typewriting machine, the combination of a carriage, tabulator indicating mechanism, and automatically operating means controlled by the movement of the carriage for shifting said indicating means.

94. In a typewriting machine, the combination of a carriage, tabulating mechanism including a key, tabulator indicating means associated with said key, and automatically operating means for shifting said indicating means.

95. In a typewriting machine, the combination of a carriage, a tabulator indicator, and automatically operating means for bringing one or another index on said indicator into the view of the operator.

96. In a typewriting machine, the combination of a carriage, tabulating mechanism including a key, tabulator indicating means associated with said key, and automatically operating means controlled by a movement of the carriage for shifting said indicating means.

97. In a typewriting machine, the combination of a carriage, a tabulator indicator, and automatically operating means controlled by the movement of the carriage for bringing one or another index on said indicator into the view of the operator.

98. In a typewriting machine, the combination of a carriage, tabulator mechanism including a series of keys, an indicator carrying indices which are adapted to register with said keys, and automatically operating means for shifting said indicator to change the indices which register with said keys.

99. In a typewriting machine, the combination of a carriage, tabulator mechanism including a series of keys which are operative at one time as denominational keys and at another time as column selecting keys, an indicator having two series of indices thereon and either of which series may be brought into cooperative relation with said keys, and

means for shifting said indicator to bring one or the other series of indices into cooperative relation with the keys.

100. In a typewriting machine, the combination of a carriage, tabulator mechanism including a series of keys which are operative at one time as denominational keys and at another time as column selecting keys, an indicator having two series of indices thereon and either of which series may be brought into cooperative relation with said keys, and automatically operating means for shifting said indicator to bring one or the other series of indices into cooperative relation with the keys depending on whether the keys are being used as denominational or as column selecting keys.

101. In a typewriting machine, the combination of a carriage, tabulator indicating means, and automatically operating means for changing said indicating means, the construction being such as to allow said automatically operating means to be rendered inoperative to change the indicating means.

102. In a typewriting machine, the combination of a carriage, tabulator indicating means, and automatically operating means controlled by the movement of the carriage for shifting said indicating means, the construction being such as to allow said automatically operating means to be rendered inoperative to shift said indicating means.

103. In a typewriting machine, the combination of a carriage, tabulating mechanism including a key, tabulator indicating means associated with said key, and automatically operating means for shifting said indicating means, the construction being such as to allow said automatically operating means to be rendered inoperative to shift said indicating means.

104. In a typewriting machine, the combination of a carriage, tabulator mechanism including a series of keys, an indicator carrying indices which are adapted to register with said keys, and automatically operating means for shifting said indicator to change the indices which register with said keys, the construction being such as to allow said automatically operating means to be rendered inoperative to shift the indicator.

105. In a typewriting machine, the combination of a carriage, tabulator mechanism including a series of keys which are operative at one time as denominational keys and at another time as column selecting keys, an indicator having two series of indices thereon and either of which series may be brought into cooperative relation with said keys, and means for shifting said indicator to bring one or the other series of indices into cooperative relation with the keys, the construction being such as to allow said automatically operating means to be rendered inoperative to shift the indicator.

106. In a typewriting machine, the combination of a carriage, tabulator mechanism including a series of keys which are operative at one time as denominational keys and 5 at another time as column selecting keys, an indicator having two series of indices thereon and either of which series may be brought into coöperative relation with said keys, and automatically operating means for 10 shifting said indicator to bring one or the other series of indices into coöperative relation with the keys depending on whether the keys are being used as denominational or as column selecting keys, the construction 15 being such as to allow said automatically operating means to be rendered inoperative to shift the indicator. 80
107. In a typewriting machine, the combination of a carriage, tabulating mechanism, 20 a tabulating scale, automatically operating means for shifting said scale, and a safety device for preventing the carriage from moving beyond a given point under an actuation of the tabulating mechanism if such 25 actuation should take place just prior to the shifting of said scale. 90
108. In a typewriting machine, the combination of a carriage, tabulating mechanism operative as a denominational selector or as 30 a column selector depending on the position of the carriage in its line of travel, denominational and column indicating means, and automatically operating means for bringing one or the other of said indicating means 35 into use accordingly as the tabulating mechanism is operative as a denominational selector or as a column selector. 95
109. In a typewriting machine, the combination of a carriage, tabulating mechanism 40 operative as a denominational selector or as a column selector depending on the position of the carriage in its line of travel, denominational and column indicating means, automatically operating means for bringing one 45 or the other of said indicating means into use accordingly as the tabulating mechanism is operative as a denominational selector or as a column selector, and means by which the tabulating mechanism may be rendered 50 operative only as a selector of one character, the construction being such as to allow said automatically operating means to be rendered inoperative, so that the indicating means corresponding to the character of selection for which the tabulating mechanism 55 is operative may remain in use indefinitely. 105
110. In a typewriting machine, the combination of a carriage, tabulating mechanism including means operative as a denominational selector or as a column selector depending on the position of the carriage in its line of travel, means for varying the point in the travel of the carriage where the tabulating mechanism ceases to be operative 60 for one character of selection and is operative for the other, denominational and column indicating means, automatically operating means for bringing one or the other of said indicating means into use accordingly as the tabulating mechanism is operative as a denominational selector or as a column selector, the construction including means which enable the point in the travel of the carriage where said automatically operating means are actuated to be varied in accordance with the variation in the point in the travel of the carriage where the tabulating mechanism ceases to be operative for one character of selection and becomes operative for the other. 80
111. In a typewriting machine, the combination of a carriage; tabulating mechanism including means operative as a denominational selector or as a column selector depending on the position of the carriage in 85 its line of travel, means for varying the point in the travel of the carriage where the tabulating mechanism ceases to be operative for one character of selection and is operative for the other and by which the tabulating mechanism may be rendered operative only as a selector of one character or the other; denominational and column indicating means; automatically operating means for bringing one or the other of said indicating means into use accordingly as the tabulating mechanism is operative as a denominational selector or as a column selector; the construction including means which 90 enable the point in the travel of the carriage where said automatically operating means are actuated to be varied in accordance with the variation in the point in the travel of the carriage where the tabulating mechanism ceases to be operative for one character 100 of selection and becomes operative for the other; and the construction being such as to allow said automatically operating means to be rendered inoperative, so that the indicating means corresponding to the character 110 of selection for which the tabulating mechanism is operative may remain in use indefinitely. 105
112. In a typewriting machine, the combination of a carriage, tabulator keys, tabulator stops controlled by said keys, there being two key controlled tabulator stops for each of said keys, and traveling tabulator stops with which said key controlled tabulator stops co-act, the two stops controlled 120 by each key being out of alignment so as to co-act with traveling tabulator stops having different paths of movement. 115
113. In a typewriting machine, the combination of a carriage, tabulator keys, tabulator stops controlled by said keys, there being two key controlled tabulator stops for each of said keys, and tabulator stops with 125

which said key controlled tabulator stops co-act, a pair of associated key controlled stops being projected to operative position at each actuation of the corresponding key.

5 114. In a typewriting machine, the combination of a carriage, two traveling tabulator stops, a tabulator key having an operating movement in but one direction and to a single given extent, two tabulator stops 10 controlled by said key and both of which are projected to operative position and into the paths of their respective traveling stops at each actuation of said tabulator key.

115. In a typewriting machine, the combination of a carriage, a set of tabulator keys, a set of column selecting stops controlled by said keys and equal in number to the latter, a set of denominational selecting stops controlled by said keys and corresponding in number to the number of keys employed, each actuation of a key projecting a column selecting stop and a denominational selecting stop as well to operative position, means coöperative with the projected column selecting stop to effect columnar selection, and means coöperative with 20 25

the projected denominational selecting stop to effect denominational selection.

116. In a typewriting machine, the combination of a carriage, a set of tabulator keys, a set of column selecting stops controlled by said keys, a set of denominational selecting stops which are likewise controlled by said keys, means co-acting with said column selecting stops to effect a columnar selection, and means co-acting with said denominational selecting stops to effect a denominational selection, the construction and arrangement of the parts being such that the position of the carriage in its line of travel 30 35 40 determines whether columnar selection or denominational selection shall be effected at an actuation of a tabulator key.

Signed at the borough of Manhattan, city of New York, in the county of New York, 45 and State of New York, this 8th day of November, A. D. 1912.
